CLOSURE FOR CONTAINERS

Ralph G. Whitlock, Los Angeles, and Lewis Sharp, Huntington Park, Calif., assignors to Federal Foundation Inc., Las Vegas, Nev., a corporation of Nevada

Application June 2, 1934, Serial No. 728,766

8 Claims. (Cl. 221—67)

Our invention relates to closures for containers and more particularly to an index closure for the inlet openings of oil and gasoline storage tanks such as used by automobile service stations. 5 Automobile motor oil is usually supplied to motorists from containers commonly known as "high boys", the latter having manually operable pumps mounted thereon. The inlet openings of these containers are readily accessible 10 thus permitting a dishonest service station owner or operator to fill these containers with low quality oil, the latter being sold as a high quality product at a high price. In an attempt to overcome this surreptitious practice, most of the 15 major oil companies have been forced to seal and distribute their oil in small cans which adds considerable expense to the distribution of oil and does not offer a solution to the problem of preventing bootleggers from distributing low quality oil in cans bearing counterfeit labels of 20 the major oil companies' products.

It is an object of our invention to provide a closure for such oil containers that will prevent access thereto without leaving evidence of said access. 25 Another object of our invention is to provide a closure which is effectively locked to an oil container to prevent bodily removal of said closure without leaving evidence thereof.

A further object of our invention is to provide 30 a closure which must be completely closed after each opening thereof in order to complete the record of access to said container.

Another object of our invention is to provide 35 a closure for an oil container that can be quickly opened and closed without the necessity of unlocking and locking the cover.

Still another object of our invention is to provide 40 a closure that is extremely simple in construction and operation.

Further objects and advantages will be made 45 manifest in the following description taken in connection with the accompanying drawings, in which:

Fig. 1 is a fragmentary vertical sectional view 50 of an oil storage tank shown in connection with a preferred embodiment of our invention.

Fig. 2 is a fragmentary front elevational view 55 of a plurality of juxtaposed oil containers showing the manner in which they are locked one to another.

Fig. 3 is a fragmentary vertical sectional view taken on the line 3—3 of Fig. 2.

Fig. 4 is an enlarged plan view of a preferred 55 embodiment of our invention looking in the direction of the arrow 4 of Fig. 1.

Fig. 5 is a vertical sectional view taken on the line 5—5 of Fig. 4.

Fig. 6 is an enlarged, detailed perspective view of a portion of the device shown in Fig. 5.

Fig. 7 is an enlarged vertical sectional view 5 taken on the line 7—7 of Fig. 5.

Fig. 8 is a vertical sectional view taken on the line 8—8 of Fig. 7.

Fig. 9 is a view similar to Fig. 8 showing the 10 operation of the parts disclosed therein.

Fig. 10 is a fragmentary side elevational view looking in the direction of the arrow 10 of Fig. 7.

Fig. 11 is a vertical sectional view taken on the line 11—11 of Fig. 7. 15

Fig. 12 is a view similar to Fig. 11 showing the operation of the parts disclosed therein.

Fig. 13 is a horizontal sectional view taken on the line 13—13 of Fig. 7. 20

Fig. 14 is a fragmentary, horizontal sectional view taken on the line 14—14 of Fig. 8.

Referring specifically to the drawings, an oil tank 10, shown in connection with the preferred embodiment of our invention, is shown in Figs. 1, 2 and 3, this tank being of conventional design with the few exceptions to be noted hereinafter. The tank 10 is formed to provide an inlet mouth 11, the latter having an upturned annular flange 12 formed therearound. Mounted within the tank 10 on the underside of the 25 top 13 thereof is an auxiliary tank 14 having an opening 15 provided therethrough as shown in Fig. 1. Extending from the underside of the auxiliary tank 14 to the front wall of the storage tank 10 is a drain pipe 17, the latter being provided with a valve 18 and plugged at its mouth by a plug 19, as shown in Fig. 3. The valve 18 is controlled from the top side 30 of the tank 10 through a suitable tube 20. Mounted on the top 13 of the tank 10 is a conventional type of lift pump 22, having a discharge pipe 23 and an intake pipe 24, the latter extending to the bottom of the tank 10 through the aforementioned opening 15. Mounted 35 on one side of the pump 22 is a crank 25 for manually actuating the piston (not shown) of the pump 22. Swingably mounted on a base portion of the pump 22 is a drip pipe 26, the upper end of the latter normally communicating 40 with the discharge end of the pipe 23 so as to deliver drippings from the pipe 23 to the auxiliary tank 14.

Mounted on the top 13 of the tank 10 over the inlet mouth 11 is a meter closure 30 comprising 45

50

55

a preferred embodiment of our invention, the closure 30 including a base 31, a housing 32, and a cover 33.

As shown in Figs. 5 and 7 the base 31 is formed to provide a concave upper portion 35 and a horizontally extending hasp 36, the latter having a slot 37 provided therethrough. Extending vertically through the base 31, as shown in Fig. 7, is a pair of holes 38 the purpose of which will be made clear hereinafter.

The housing 32 is cast of metal to provide a cylindrical body 40, having an annular flange 41 provided on one end thereof, as shown in Fig. 7. The upper wall of the cylindrical body 40 is formed to provide a rectangular opening 42. As shown in Figs. 11 and 13, the inside of the housing 32 is formed to provide a horizontal, cylindrical cavity 44, a token magazine 45, and a cavity 46, the latter being disposed above the cavity 44 and the token magazine 45, as shown in Fig. 11. The body 40 is secured to the top 13 of the tank 10 by means of a pair of cap screws 48, the latter extending upward through the top 13 and the holes 38 of the base 31 and into the body 40, as shown in Fig. 7.

Slidably mounted in a hole 49 provided at one end of the body 40, as shown in Figs. 7 and 14, is a latch pin 49a having a chamfered face 49b and a pin 49c, the latter engaging a suitable slot as shown to prevent rotation of the latch pin 49a. Provided in the hole 49 in back of the latch pin 49a is a compression spring 49d to urge the latch pin to the position in which it is shown in Fig. 14, also mounted in the body 40, as shown in Fig. 13, is a spring pressed ball 50, the purpose of which will be made clear hereinafter.

Fixed on one end of the cylindrical body 40 is a plate 51, the latter being aligned by means of a stud 52 received by a suitable aperture in the end of the body 40. The plate 51 is formed to provide an opening 53 at one side thereof as shown in Fig. 10, a receptacle 54 being formed on the plate 51 below the opening 53 for a purpose to be described hereinafter. The plate 51 is secured in position on the end of the body 40 by a screw 55, a portion of the head being broken off to prevent removal of the screw 54.

Provided in the end of the body 40 adjacent the plate 51 is a non-reverse mechanism 56 to be described hereinafter. Fixed to the end of the body 40 opposite the plate 51 is a somewhat similar plate 57 fixed to the body 40 by means of a screw 58, the latter being broken off after installation in a manner similar to that described in relation to the screw 55. The plate 57 is aligned in relation to the body 40 by means of a stud 59 received by a suitable aperture provided in the body 40, as shown in Fig. 7. Formed through the plate 57 is an opening 60, positioned in axial alignment with the aforementioned magazine 45, as shown in Fig. 13. Extending through the opening 60 of the plate 57 and into one end of the magazine 45 is a lock plug 62 having a bolt 63 extending into a suitable aperture 64 in the body 40, as shown in Fig. 13. The bolt 63 is extended and retracted by means of suitable combination lock mechanism (not shown) within the plug 62, the lock mechanism having a shaft 65 upon which a dial 66 is removably mounted. Provided on one side of the plug 62 is a pin 67 which is received by a suitable keyway in the dial 66 for the purpose of locating the plug 62 in proper circum-

ferential relation with the magazine 45. Slidable within the magazine 45 is cup 70 having a button 71 provided centrally thereof, a compression spring 72 being interposed between the lock plug 62 and the cup 70. Provided in the magazine 45 is a plurality of tokens 73, each of these bearing suitable indicia to distinguish it from the others.

The cover 33 is cast of one piece of metal to provide a plate 80 normally positioned concentrically over the mouth 11 of the tank 10, as shown in Fig. 5. Formed integral with the plate 80 and extending downward into the mouth 11 is an annular flange 81 the purpose of which will be made clear hereinafter. Provided on the upper side of the plate 80 is an annular rim 82 having a lip 83 formed on one side thereof. Extending horizontally from one side of the plate 80 is a hasp 84 having a slot 85 for receiving an apertured lug 86 provided on the upper side of the top 13 of the tank 10. The plate 80 is swingably mounted to the housing 32 by means of a pair of bands 88 and 89, the latter being formed integral with the plate 80 and embracing the housing 32, as shown in Figs. 4 and 5. Formed on the inside of a portion of the band 89 is a plurality of notches 90, as shown in Fig. 8.

The aforementioned non-reverse mechanism 56 includes a pair of pawls 95 and 96, the lower ends of these being fixed to pins 97 which are rotatably mounted in the body 40 as shown in Fig. 8. Fixed on the upper sides of the pawls 95 and 96 are spring fingers 98, similar spring fingers 99 being fixed to the underside of the pawls 95 and 96, the fingers 99 being longer than the fingers 98 and provided with lugs 100 at the upper extremities thereof. Pivotally mounted on a cylindrical boss 103 of the body 40 is an oscillating collar 104, the latter being shown in detail in Fig. 6. The collar 104 is formed to provide shoulders 105 and 106 and an upstanding ridge 107 having a groove 108 formed therein. Extending outward from the collar 104 in central alignment with the ridge 107 is a pin 109. Rotatably mounted on the aforementioned stud 52 of the plate 51 is a control plate or shutter 111, having an opening 112 formed therethrough as shown in Fig. 8, the opening 112 being normally disposed in registration with the aforementioned opening 53 of the plate 51. The periphery of the plate 111 is formed to provide a pair of shoulders 114 and 115 and an arcuate slot 116. As shown in Figs. 8 and 9, the plate 111 is pinned to the band 89 by pins 118. It will be noticed especially in Figure 5 that an anchoring member C is provided, which provides means for journaling the pin 109 of the collar 104. This anchoring member C is formed with oppositely arranged inclined or bevelled sides, A and B, respectively. The part of the anchoring member which has the collar 104 mounted thereupon is formed cylindrically as in D, and the collar is rotatedly mounted upon this part D so that this collar may be rocked in either of opposite directions, to the right or to the left; in either case this collar, when shifted by means hereinafter shown, comes to rest as soon as the shoulder, 105 or 106 thereof, engages either inclined or bevelled side, A or B, of the anchoring member C.

Mounted in the cavity 46 of the body 40 is a counter 120 having a lever 121, the latter being actuated by a plunger 122 which extends into a suitable recess 123 provided in the band 89, the counter 120 being visible through the aforemen-

tioned opening 42 of the body 40, as shown in Fig. 4.

Operation.

When it becomes necessary to replenish the supply of oil in the tank 10, the operator raises the cover 33 from the position shown in Fig. 8 to that shown in Fig. 9. As the cover 33 is thus raised, the control plate 111 fixed to the band 89 is rotated from the position shown in Fig. 8 to that shown in Fig. 9, the opening 112 of the plate 111 being brought into alignment with the magazine 45 of the body 40 so as to receive one of the tokens 73. It will also be noted that rotation of the plate 111 causes the shoulder 114 thereof to contact the pin 109 of the collar 104 so as to swing the latter to the position shown in Fig. 9 thus allowing the pawl 95 to drop out of contact with the notches 90 of the band 89 and simultaneously forcing the other pawl 96 into engagement with the notches 90. After replenishing the supply of oil in the tank 10, the cover 33 is returned to closed position, the non-reverse mechanism 56 returning to the position shown in Fig. 8. As the plate 111 is rotated from the position shown in Fig. 9 to that shown in Fig. 8, the opening 112 carries the token 73 from the stack of tokens in the magazine 45 into alignment with the opening 53 of the plate 51, the aforementioned spring pressed ball 50 then causes the token 73 to fall through the opening 53 and into the receptacle 54. The operator after supplying the tank 10 with oil, takes the discharged token and returns this with his report so as to complete the record of that particular dump. As the cover 33 is opened the plunger 122 shown in Fig. 11, is raised by the recess 123 of the band 89 to the position shown in Fig. 12, thus actuating the lever 121 causing the counter 120 to indicate that access has been had to the tank 10. The non-reverse mechanism 56 prevents closing the cover 33 after starting to open the same until the cover 33 is completely opened, it being clear that the pawl 95 allows the band 89 to rotate only in clockwise direction as viewed in Fig. 8, the pawl 96 remaining in inactive position during the opening of the cover 33. However, when the cover 33 is fully open, the collar 104 shifts the pawl 96 into engagement with the notches 90 and allows the pawl 95 to move to inactive position so that the cover 33 may be moved in anti-clockwise direction to closed position, it being noted that the pawl 96 prevents reverse movement of the cover 33 during the closing movement thereof until the cover is fully closed. The aforementioned annular flange 81 on the under side of the plate 80 prevents access to the mouth 11 of the tank 10 until the cover 33 is opened sufficiently to permit the pawl 95 to prevent reverse movement of the cover 33.

The aforementioned latch pin 49a mounted in the body 40 is for the purpose of preventing the insertion of a token into the discharge opening 53 of the plate 51 and opening and closing the cover 33 without discharging an additional token, it being clear that the latch pin 49a prevents rotation of the control plate 111 while a token remains in the opening 112 thereof.

The supply of tokens 73 is replenished from time to time by an authorized inspector who unlocks and removes the lock plug 62 from the magazine 45 and inserts a fresh supply of tokens into the magazine 45 and replaces the lock plug 62, as shown in Fig. 13. As aforementioned, the dial 66 of the lock plug 62 is removable so that it may

be taken away by the inspector so as to further prevent unauthorized access to the token magazine 45. If the supply of tokens within the magazine 45 should become exhausted, the button 71 of the cup 70 enters the arcuate slot 116 of the plate 111 and locks the plate 111 against rotation thus preventing opening of the cover 33 until a fresh supply of tokens is placed in the magazine 45.

As the tanks 10 are often kept outside, they must be locked together to prevent them from being stolen, it being clear that each tank might be carried away individually but that a group of tanks securely locked together would be more difficult to steal. As shown in Fig. 2, a plurality of tanks 10 may be juxtaposed so that the hasps 36 of the bases 31 receive the apertured lugs 86 of adjacent tanks, the hasps 84 of the plates 80 being super-imposed on the hasps 36 and retained on the lugs 86 by means of suitable padlocks 125.

Oil is dispensed from the tank 10 by placing a suitable receptacle (not shown) on the plate 80 and rotating the crank 25, the drip pipe 26 being swung to one side to allow oil discharged from pipe 23 to fill the aforementioned receptacle. If the receptacle is overfilled the overflow oil is received by the plate 80 and delivered by the lip 83 to a suitable opening 126 into the auxiliary tank 14, it being also clear that the drippings from the pipe 23 are received by the drip pipe 26 and are also returned to the auxiliary tank 14. From time to time the tank 10 is drained by removing the plug 19 from the pipe 17 and opening the valve 18. The provision of the tank 14 is for the purpose of receiving overflow oil and drippings so as to prevent access to the interior of the tank 10 except by means of opening the cover 33 of the closure 30. The auxiliary tank 14 also prevents dust and impurities from being washed into the tank 10, thus preventing pollution of the oil contained therein.

Although we have shown and described but one preferred form of our invention, it is to be understood that many changes and modifications might be made therein without departing from the spirit of the invention and the scope of the appended claims.

We claim as our invention:

1. In a device as described, in combination with a tank having an inlet, a cover cap engaging said inlet to close the same, a fixed sleeve having a sight opening, a register visible through said opening, a pair of collars mounted upon said sleeve rotatably, said cover cap serving as a crank for actuating said sleeve cap, and means operated by said collars as they move for rendering said register active.

2. In a device as described, in combination with a tank having an inlet, a cover cap fitted into said inlet to close the same, a fixed bearing, means swingingly mounting said cover cap upon said bearing retractedly, and a visual register in said bearing operated by said cover cap as it swings.

3. In combination with a container having an inlet, a fixed cylinder thereon having a window, a register visible through said window, mechanism inside of said cylinder for operating said register, means releasably covering said inlet, and means swivelly engaging said cylinder as said means uncovers said inlet for actuating said mechanism.

4. In combination with a tank having an inlet, a fixed cylinder thereon displaying a permanent register, means concealed in said cylinder for ac-

tuating said register, and a crank for operating said means, said crank shaped to provide a flat cap designed to releasedly cover said inlet.

5. In combination with a container having an inlet, a fixed hollow body thereon containing a displayed register counter mechanism, means rotating externally upon said hollow body for actuating the within counter mechanism, and a cap carried by said means adapted to seat in said 10 inlet.

6. In a device as described, means controlling the closing of a tank inlet, a token carrier, means whereby said carrier is rotated, means operated with said carrier for actuating the controlling 15 means, and a token ejector engaged by the token as the carrier is rotated to cause the token to be deposited outside said controlling means.

7. In a device as described, a tank having an inlet, a fixed cylinder containing a check magazine, a check carrier and depositor being auto- 20

matically and successively supplied by said magazine, inlet covering means movably mounted upon said cylinder and being actuated in time with said carrier and means responsive to the presence or absence of a check in said magazine for 5 controlling said carrier.

8. In a device as described, a container having an external pocket, a cylinder secured thereto adjacent to the mouth thereof, a cover hinged to said cylinder to close or open the mouth there- 10 of, a plurality of tokens within said cylinder, means responsive to the opening and closing movement of said cover to discharge one of the tokens from said stack into said pocket for manual removal, and means whereby said cover is 15 automatically locked with relation to said cylinder mouth when the cylinder is without tokens.

RALPH G. WHITLOCK.
LEWIS SHARP. 20
